United States Patent Office

Des. 179,668
Patented Feb. 5, 1957

179,668

EGGHOLDER OR SIMILAR ARTICLE

Elwyn Louis Ward, Manhattan Beach, Calif.

Application June 4, 1956, Serial No. 41,751

Term of patent 7 years

(Cl. D44—4)

Fig. 2

Fig. 3

Fig. 4

Fig. 5

Fig. 1 is a perspective view of an egg holder or similar article showing my new design;

Fig. 2 is a vertical section on line 2—2 of Fig. 1;

Fig. 3 is a vertical section on line 3—3 of Fig. 1;

Fig. 4 is a vertical section on line 4—4 of Fig. 1; and

Fig. 5 is a vertical section on line 5—5 of Fig. 1.

I claim:

The ornamental design for an egg holder or similar article, substantially as shown.
